UNITED STATES PATENT OFFICE.

PAUL O. MATTSON, OF DENVER, COLORADO.

FOLDING EASEL.

Application filed April 6, 1926. Serial No. 100,138.

This invention relates to easels such as are used for holding relatively small pictures on tables, stands, and the like though the principle of the device might be applied to 5 large easels also.

The general object of the invention is to provide an easel which is very simple, cheaply made and which may be folded into compact form.

10 A further object is to provide an easel formed of two half sections hinged to each other so that these sections may be turned into angular relation to each other or into a facing relation when the easel is to be 15 folded.

A still further object is to provide an easel of this character which is ornamental in character and which is provided with an auxiliary means for steadyng the two halves 20 of the easel when these two halves are unfolded or put in applied position.

My invention is illustrated in the accompanying drawings wherein:—

Figure 1 is a face view of an easel constructed in accordance with my invention;

Fig. 2 is an edge view of the easel showing the two sections folded upon each other into confronting relation;

Fig. 3 is a section on the line 3—3 of Figure 1;

Fig. 4 is a side elevation of the easel in its applied position;

Referring to these drawings it will be seen that the easel consists of two sections A and 35 B, these sections being alike. Each of these sections has an upwardly and inwardly ex-

40 tends portion 10, angularly extended at its upper end in a horizontal plane as at 11, and each portion 10 at its lower end is angularly extended as at 12 parallel to the extension 11, this part 12 being provided with the downwardly extending foot 13.

Formed integral with the portion 10 is a 45 forward foot 14 which is offset with relation to the portion 10 so as to provide a picture supporting shoulder 15, preferably projecting upward and outward.

Between the foot 13 and the foot 14 the lower end of each section of the easel is cut 50 away, as at 16, and hinged to each foot 12 on the rear face thereof, is an auxiliary or bracing foot 17 which may be turned into aligned relation to the lower end of the corresponding section or into nearly right 55 angular relation thereto.

Where easels are to be used for relatively

light and small pictures there is not ordinarily any necessity for the wings or bracing feet 17 and these may be omitted but where the easels are relatively tall and intended to support relatively heavy pictures or pictures of large area, these wings 17 are particularly desirable.

By forming the shoulders 15 at an upward and outward inclination, the picture disposed upon these shoulders will act to hold the two sections of the easel from either outward or inward movement and the wings 17 when in use, will also act to impede any outward movement of the two sections of the easel. The easel, being formed in two flat sections hinged to each other, may be folded up into the position shown in Figure 3 and thus packed flat for transportation. The hinges do not support any of the strain on the easel or the weight of the picture and, therefore, there is no tendency of the hinges to become loose as is the case in the ordinary easel where any lateral strain tends to racking the hinge. The easel is small, can be readily made, and adapts itself to many ornamental and useful purposes. While in most cases the easel will be made of wood, I do not wish to be limited thereto as it might be made of paste board, composition, or any material which would be suitable for the purpose. Obviously the exact form of the easel may be changed in many ways without departing from the spirit of the invention as defined in the appended claims.

I claim:—

1. An easel formed of two lateral sections hingedly connected on a vertical middle line whereby said sections may be turned either into a confronting relation or into an angular relation, each of said sections being formed at its lower end with an outwardly projecting shoulder upon which a picture may be supported, and wings connected to the two lateral sections at their lower ends and thereby adapted to be turned toward or from the rear face of the corresponding section into or out of angular relation thereto, said wings having their lower edges on a level with the lower edges of each section and thus being adapted to rest on a supporting surface and when in angular relation bracing the easel in an upright position.

2. An easel consisting of two like sections hingedly connected to each other along a

vertical middle line whereby the sections may be folded into confronting relation or into an angular relation, each section at its lower end being cut away to thereby provide a rear foot and a front foot and each section at its lower end being formed to provide an outwardly projecting shoulder upon which a picture may rest, and wings, one for each section, hingedly connected to the forward edge of the rear leg of the section at the lower end thereof for movement toward or from the rear face of the section and into angular relation thereto.

3. An easel consisting of two like hinged sections, each of these sections being formed to provide an upwardly and inwardly inclined portion having a horizontal portion

at its upper end, the lower end of the section being formed with a horizontal portion extending in opposite directions beyond the lower end of the upwardly and inwardly inclined portion, and formed at its ends with depending feet and formed to provide a shoulder above the front foot upon which a picture may rest, and a wing hinged to the rear foot of each section and beneath said horizontal portion and adapted to be shifted from a position aligned with the section to a position at an angle thereto and acting as a brace.

In testimony whereof I hereunto affix my signature.

PAUL O. MATTSON.
